CLAIM

The ornamental design for a barbecue grill, as shown.

DESCRIPTION

FIG. 1 is a left side view of a barbecue grill showing my new design,

FIG. 2 is a right side view thereof;

FIG. 3 is a rear view thereof;

FIG. 4 is a front view thereof; and,

FIG. 5 is a top view thereof.

The gas hose is shown broken away in FIGS. 1-4 and is understood to represent indeterminate length.
